J. COLLmann.
RULING MACHINE.

No. 10,361.

Patented Jan. 3, 1854.

UNITED STATES PATENT OFFICE.

JOHN COLLMANN, OF SILVER CREEK, ILLINOIS.

RULING-MACHINE.

Specification of Letters Patent No. 10,361, dated January 3, 1854.

To all whom it may concern:

Be it known that I, JOHN COLLMANN, of Silver Creek, in the county of Stevenson and State of Illinois, have invented a new 5 and useful Improvement in Ruling-Machines; and I do hereby declare that the following is a full, clear, and exact description of the construction and operation of the same, reference being had to the annexed 10 drawings, forming part of this specification, in which—

Figure 1 is a top view of the box with the cover removed. Fig. 2 is a vertical section upon the line $x-x$ of Fig. 1. Fig. 3 is a 15 similar section upon the line $y-y$ of same figure.

Similar letters of reference in the several figures denote the same part of the machine.

My invention refers to an improvement in 20 machines for ruling parallel lines upon copper plates and other surfaces, and has for its object the moving laterally of the way upon which the ruling carriage runs.

It consists in moving the box to which the 25 way is attached, along a bar passing through it, by the action of a cam working against a plate alternately sliding upon and secured to the traversing bar, the operation being performed by means of a lever fastened to 30 the cam, the movement of which is regulated by an adjustable stop, thus limiting the advance of the box and regulating the distance between the lines.

In the drawings a is the box, b the way 35 upon which the ruling carriage runs, and c the bar passing through and supporting the box. Around the bar c , and capable of sliding upon it is the case d , having between its rear extremity and the partition e of the 40 box, the spring f wound around the bar c .

Projecting from the forward end of the box a , is the ear g , in which rests the spindle h of the cam m . The face of this cam presses against the plate k of the case d . 45 Attached to the cam m is the lever l , the movement of which is limited by the stop n , which by means of the screw p moves backward and forward in the chamber q . In the side of the case d works the screw r so 50 that its extremity shall press against the bar c , and secure the case to the bar.

The operation of my machine is, as follows: The traversing bar c is secured at each extremity to uprights, and the stop n adjusted to suit the spaces to be made between 55

the lines. The screw r is loosened, which allows the spring f to act, and throw forward the plate k , at the same time bringing the lever l against the stop n ; the screw r is then tightened securing the case d to the 60 bar c , the plate k being against the face of the cam m and the lever l against the stop n , the position assumed by the action of the spring f . The lever l is then carried in the direction of the arrow, causing a pressure of 65 the face of the cam m against the edge of the plate k , moving the box a on the bar c a distance proportional to the arc passed over by the extremity of the lever l ; this space being as before stated regulated by the screw 70 p upon which the stop n moves. After the lever l has completed its movement, the screw r is again loosened, causing the plate k to fly forward by the action of the spring 75 f against the case d , and the other parts to resume the positions assumed on the first 80 loosening of the screw r ; which is immediately re-tightened and the lever l carried forward with the effect before produced. In this manner the operation continues, the 85 screw r being loosened to permit the action of the spring f , and then tightened to fasten the case d to the traversing bar c , while the box a is moved the requisite distance by the lever l . As the box a moves on the traversing bar c , the way b is carried forward laterally, and the lining carriage drawn over it in the usual manner after each movement of the box a . The box is kept from slipping by means of the spring s between the bar c 90 and the side of the box. The slot t in the side of the box prevents the screw r from interfering with the movement of the box along the traversing bar.

What I claim as my invention and desire 95 to secure by Letters Patent, is—

The case d alternately sliding upon and secured to the bar c as specified, in combination with the cam m , lever l , spring f , and stop n , arranged and operating as described, 100 for moving the box a upon the traversing bar c any required distance, substantially as, and for the purpose, herein fully set forth.

In testimony whereof, I have hereunto signed my name before two subscribing witnesses. 105

J. COLLMANN.
